UNITED STATES PATENT OFFICE.

GUSTAVE ADOLPH OLLSEN, OF PROVIDENCE, RHODE ISLAND.

ATTACHMENT FOR FAUCETS.

No. 812,082.

Specification of Letters Patent.

Patented Feb. 6, 1906.

Application filed May 16, 1905. Serial No. 260,693.

To all whom it may concern:

Be it known that I, GUSTAVE ADOLPH OLLSEN, a citizen of the United States, and a resident of Providence, in the county of Providence and State of Rhode Island, have invented a new and Improved Attachment for Faucets, of which the following is a full, clear, and exact description.

This invention relates to attachments for faucets; and it consists, substantially, in the details of construction and combinations of parts hereinafter more particularly described, and pointed out in the claims.

One of the principal objects of the invention is to provide a device by which a pail, pan, or other vessel may be conveniently suspended on a faucet or spigot to be filled with water or other liquid drawn from the discharge-spout thereof.

A further object is to provide a device for this purpose which is exceedingly simple in construction and cheap to manufacture, besides being easily and quickly applied and removed and possessing the capacity for long and repeated service.

The above and additional objects are attained by means substantially such as are illustrated in the accompanying drawings, forming a part of this specification, in which similar characters of reference indicate corresponding parts in all the views.

Figure 1 is a side view of a faucet or spigot having my improved attachment applied thereto for use. Fig. 2 is a plan view of one form of my improved attachment. Fig. 3 is a longitudinal sectional view on the line 3 3 of Fig. 2. Fig. 4 is a top plan view of a modified form of the device, and Fig. 5 is a longitudinal sectional view thereof, taken on the line 5 5.

Before proceeding with a more detailed description it may be stated that in the forms of my improved attachment herein shown I provide a device of special construction for holding or supporting the handle of a vessel to be filled from a faucet, said device having special means whereby the same may be removably attached to the faucet and removed therefrom when desired, and while I have herein represented my improvements in certain preferred embodiments it will be understood, of course, that I do not limit myself thereto in precise detail, since immaterial changes therein may be resorted to coming within the scope of my invention.

Reference being had to the drawings by the

designating characters marked thereon, 1 represents an ordinary faucet or spigot having the usual discharge-spout 2 and the handle 3 for manipulating the controlling-valve (not shown) thereof, said handle being mounted upon the stem 4 of said valve, working in what is sometimes termed the "dome" 5 of the faucet.

As shown in Figs. 1 and 2, my improved attachment for a faucet is constructed of a single piece of sufficiently stout wire, having the free extremities thereof crossed at 6, whence they are bent outwardly from each other semicircularly, as at 7, to form an approximately circular horizontal clasp 8 for fitting upon said dome 5 of the faucet, as shown. After being thus formed the two members of the said wire are crossed at 9 in opposite directions, whence they are carried forwardly and outwardly or beyond the clasp 8, as indicated at 10, finally being bent outwardly at 11 and returned at 11^a substantially in parallelism in the direction of and laterally beyond the clasp 8, then forwardly at 12 and 80 shaped into adjacent vertically-disposed sprung loops 13, connected by a central arched portion 14. In applying this form of the device to the dome of the faucet the clasp 8 is applied to said dome in such manner that 85 the central arch 14 of the device will rest upon the upper curved surface of the discharge-spout 2 of the faucet, while the vertically-disposed sprung loops 13 receive or clamp between them the opposite sides of the 90 said discharge-spout. In this way a stable support is had for the device upon the faucet, and the forward and return portions 10 and 11^a of the two members of the wire being bent or upturned at 15 to form retaining 95 hooks or lips 16 it is apparent that by applying the bail or handle 17 of a vessel behind either one or both of said hooks or lips the vessel will be conveniently supported beneath the discharge-spout of the faucet in 100 such manner as to be readily filled therefrom. The construction of this form of the device is such that with each increment of weight to the vessel suspended therefrom the tighter will the loops 13 clamp or bind 105 between them the sides of the discharge-spout of the faucet, this effect being especially due to the fact that the forwardly and outwardly bent portions 10 of the members of the device are also slightly inclined upwardly and rearwardly—as indicated at 18 in Figs 1 and 3, for instance—so that as the weight of the ves-

sel increases the same tends to draw downwardly upon the said portions of the device, with the result that the said loops 13 are carried in the direction of each other, thereby 5 tightly hugging the sides of the discharge-spout 2 of the faucet.

As shown in Figs. 4 and 5, instead of constructing the device of sprung wire I form the same of a single piece of metal, comprising an approximately circular clasp 19 to fit around or upon the dome 5 or any other projection of the faucet 1, projecting from which 10 clamp is an extended upturned hook 20, laterally of which and at the point of intersection of said hook 20 with the said clasp 19 are the oppositely-disposed downwardly-turned clamping members 21. When this form of the device is employed, the clasp 19 may be applied or fitted in place by bending it to fit 15 the dome 5, while the clamping members 21 may be similarly bent to embrace the discharge-spout of the faucet as the same is embraced by the sprung loops 13. (Shown in Figs. 1, 2, and 3.) This form of the device 20 may, however, be formed entirely of spring metal, so that the parts or elements thereof may be sprung into place rather than bent to be fitted upon the faucet.

It is thought the construction and operation of my improvements will be thoroughly 25 understood from the foregoing and also that the advantages thereof will be quite apparent.

Having thus described my invention, I 30 claim as new and desire to secure by Letters Patent—

1. A device of the character described, comprising a clasp for attachment to an upright portion of a faucet, a clamp for adjacent side 35 portions of the discharge-spout of the faucet, and a hook for supporting the bail of a vessel.

2. A device of the character described, comprising a single piece of wire having the ex-

tremities thereof twisted together at the ends, thence curved outwardly and crossing each 45 other to form an approximately circular clasp, the two members of the wire then being bent horizontally beyond the clasp, thence laterally and returned in the direction of the clasp and terminating in vertically-disposed sprung loops having a centrally-disposed transverse connecting-arch. 50

3. A device of the character described, comprising a single piece of wire having the extremities thereof twisted together at the ends, 55 thence curved outwardly and crossing each other to form an approximately circular clasp, the two members of the wire then being bent horizontally beyond the clasp, thence laterally and returned in the direction 60 of the clasp and terminating in vertically-disposed sprung loops having a centrally-disposed transverse connecting-arch, the returned portions of said members being inwardly and upwardly inclined. 65

4. A device of the character described, comprising a single piece of wire having the extremities thereof twisted together at the ends, thence curved outwardly and crossing each other to form an approximately circular 70 clasp, the two members of the wire then being bent horizontally beyond the clasp, thence laterally and returned in the direction of the clasp and terminating in vertically-disposed sprung loops having a centrally-disposed transverse connecting-arch, each of the connected portions of the device beyond 75 the clasp being upturned to form a hook:

In testimony whereof I have signed my name to this specification in the presence of 80 two subscribing witnesses.

GUSTAVE ADOLPH OLLSEN.
